UNITED STATES PATENT OFFICE.

RAYMOND C. PENFIELD, OF NEW YORK, N. Y.

MACHINE FOR HANDLING BRICKS.

974,292.

Specification of Letters Patent.

Patented Nov. 1, 1910.

Application filed October 8, 1908. Serial No. 456,693.

To all whom it may concern:

Be it known that I, RAYMOND C. PENFIELD, a citizen of the United States of America, residing at New York city, in the 5 county of New York and State of New York, have invented certain new and useful Improvements in Machines for Handling Bricks, of which the following is a specification, reference being had therein to the accompanying drawing.

My present invention relates to a machine for handling bricks, said machine being of the class employing a method described and claimed in my co-pending application for Letters Patent, filed October 8, 15 1908, Serial Number 456,692, which method consists essentially in lifting a mass of material, such as brick, by power applied horizontally at the ends of the base of the mass 20 of material, said base being shorter than the rest of the mass and consisting of a number of detached blocks laid close to each other without any openings between. In the same co-pending application, I have also described and claimed a form of mechanism 25 for carrying the method into effect, which mechanism comprises essentially a pair of clamping members designed to exert their pressure laterally against the ends of the shorter basic layer of bricks, and said clamping members being actuated by suitable leverage means carried by a vertically-disposed frame.

My present invention consists in novel and 30 ingenious mechanism for accomplishing the same object as that sought for in my co-pending application referred to, and performing the same method of operation. It differs, however, in mechanical details for 35 effecting the clamping at the ends of the lower tier of bricks.

The invention, therefore, consists essentially in the construction, combination and arrangement of parts, and in numerous details and peculiarities thereof, substantially 40 as will be hereinafter described and claimed.

In the accompanying drawings, illustrating 45 my invention, Figure 1 is an elevational view of my improved machine for handling 50 bricks. Fig. 2 is a vertical side elevation in partial section on the line 2, 2 of Fig. 1. Fig. 3 is a sectional plan view on the line 3, 3 of Fig. 1. Fig. 4 is a detail rear view of the leverage devices in the lower portion of 55 the machine. Fig. 5 is a detail elevation of one of the clamping plates.

Similar characters of reference designate corresponding parts throughout the different figures of the drawings.

The main frame of the apparatus is of a 60 general upright construction, in order that it may lie alongside of the stack formation of brick in proper position to permit the clamping members at the bottom end thereof to be projected at the ends of the shorter 65 basic layer for the purpose of tightly clamping the latter, and so also that the upper laterally-turned portion of the frame may project over the mass of brick so as to be in a position to be suitably engaged by a lifting 70 crane or other device at a point where the mass can be supported without interfering with its center of gravity. This main frame in the present example of the invention consists essentially of two inclined bars 1, 1 secured near their upper ends to central uprights 9, which are turned at their upper ends, at 2, said laterally-turned upper ends being secured together by means of a bolt 3. Between the laterally-turned ends 2 a horizontal lever 4 is fulcrumed upon said bolt 3, and to this horizontal lever is pivoted an eye 5, to which a lifting crane may be attached. At the opposite end of the lever 4 from its pivot 3 a cross head 6 is pivotally hung by means of a bolt 7. To the opposite ends of the cross head 6 are pivoted two long inclined links 8 which extend downwardly alongside of the inclined bars 1, 1 of the main frame. The frame also comprises the 75 aforesaid pair of parallel uprights 9, 9 located between the inclined bars 1, 1 said uprights being united to the bars 1, 1 near the top of the frame, and at the bottom being secured to a block 10 which is made integral 80 with or is firmly attached to a base frame 11. To this base frame 11 the lower ends of the inclined bars 1 are bolted as shown in Fig. 1. The base frame 11 is a horizontal rectangular structure illustrated fully in Figs. 2 and 85 3. Its form may vary widely provided only that it is so shaped as to accommodate therein the mechanical elements at the base of the machine, including the clamping plates 90 and the devices for operating them.

The lower ends of the long links or arms 95 8, 8 are pivoted to long transverse levers 12 which cross each other, and are placed substantially horizontal, and the opposite ends of which are rigidly attached to horizontal 100 rock shafts 13 suitably journaled in the lower frame 11. These rock shafts, more- 105 110

over, are provided with rigid crank arms 14, each shaft having preferably two of these arms, and said arms are pivoted to the rear faces of the clamping plates 15. In order to enable this pivoting to be accomplished with facility and strength, I preferably provide on the rear faces of said clamping plates pairs of ears *a a* as shown in Fig. 5, the crank arms 14 being pivoted between the members of these pairs of ears. The clamping plates 15 have vertical faces as shown in Figs. 1 and 2, and preferably at the top and bottom they are built with broad, flat flanges 16 which, if desired, may rest beneath the overhanging edges of the upper mass of brick which projects over the ends of the shorter basic layer. I am not restricted, however, to making the clamping plates 15 with these broad flanges 16, as they may be omitted if desired, though in that case the plates themselves might be made sufficiently thick to furnish broad upper edges. In a word, however, the detailed construction, shape, dimensions and general plan of the clamping plates may vary within wide limits, it being only essential that they should be so made as to be able to exert a very strong clamping effect against the ends of the lower tier of brick. It is found desirable in the operation of clamping plates of this kind, in order to keep the clamping faces vertical during the movement of the clamps, that I should use additional arms similar to the arms 14 and pivoted to the clamping plates and also to the frame, the distance between the pivotal centers being the same as that between the pivotal centers of the crank arms 14, so that in effect I thus provide a parallel motion for the clamps 15. These supplemental links are designated 17. This clamping and lifting machine, obviously, is designed for use primarily with burned brick after the same has been hacked up in stack formation with the lower layer solid and the upper mass similarly set close for purposes of shipment and otherwise. It is possible, however, that the machine might be utilized with a mass of loosely set brick arranged for drying or burning, provided, of course, the lower layer is set solid and without any openings between the members or units. The pair of clamps 15, when the machine is about to be used, apply their gripping faces to the ends of the lower course of bricks and by tightly clamping the same enable the mass of superposed bricks to be lifted as the result of the horizontal strain imparted to the basic layer. At times, however, if desired, a vertical lifting strain may be exerted by the upper edges or faces of the clamps beneath the overhanging parts of the upper mass simultaneously with the lateral clamping effect produced by binding the clamps horizontally against the ends of the lower course. The employment of long

levers, as 12, at the base of the machine, which are actuated by the long links running to the top of the frame, enables a very strong clamping effect to be produced.

In the operation of the machine, some suitable lifting crane or other supporting means will be caused to engage the eye 5 at the top of the frame, and this will oscillate the lever 4 upon its pivot and draw the two links 8, 8 upwardly, which will rock the shafts 13 in their bearings, thereby actuating the crank arms 14 which are pivoted to the clamping plates 15, and forcing the clamping plates toward each other and against the ends of the short lower tier of brick. A torsional strain is imparted to the shafts 13, 13, as the result of the action thereon of the long levers 12, and the power with which the cranks 14 urge the clamps 15 against the brick is very great indeed. In other machines having a like function and similar purpose, some of which I have invented and patented, and others of which certain of my contemporaries have patented, the initial lifting movement on the frame operates automatically to actuate clamping devices at the base and cause them to engage the brick after a certain fashion, entirely different, however, from my present machine. But in those cases the lever at the top of the vertically-disposed main frame has generally been arranged so that when the crane lifts the machine certain thrust bars will operate downwardly against levers at the base of the machine for the purpose of causing the clamps to do their duty; but in my mechanism, in the present instance, I have departed widely from that function by substituting therefor an action which is such that when the crane lifts the lever at the top of the frame, the links connected to said lever through the cross head, as described, will lift the long levers at the base, so that the operation does not involve a thrusting action downwardly, but a pulling action upwardly. As the result of this, the very strong and effective leverage action which I have above described is successfully practiced, and I am enabled to grip with perfect ease a lower course of brick in such a way as to lift and transport the entire mass.

Having thus described my invention, what I claim as new and desire to secure by Letters Patent, is:

1. A brick handling machine, comprising a main frame, a pair of clamps at the base for gripping the brick, means for actuating said clamps consisting essentially of horizontal rock shafts having rigid arms thereon which are pivotally connected to the clamps to provide a parallel motion mechanism for each clamp, crosswise arranged levers secured to said rock shafts, lifting bars pivotally connected to the ends of said le-

vers, and means for jointly actuating said lifting bars.

2. A machine for handling brick, comprising a main frame, a pair of clamps, shafts 5 having rigid arms thereon which are pivotally connected to the clamps to provide a parallel motion mechanism for each clamp, crosswise arranged levers secured to the shafts, lifting means pivotally connected to 10 said levers, and means for jointly actuating said lifting means consisting of a lever at the top of the machine to which the lifting crane applies its power.

3. A machine for handling masses of material, comprising a vertically disposed frame, a pair of clamps at the lower end for exerting pressure against the opposite ends of the lower course of brick, rock shafts supported alongside of said clamps, rigid arms 20 on said rock shafts pivotally connected to the clamps, long horizontal levers arranged crosswise of each other and of the machine and rigidly attached to the rock shafts, and means whereby the lifting strain which 25 raises the entire machine is applied to the ends of the long levers.

4. In a machine for handling brick and other masses of material, having a lower tier shorter than the rest of the mass, the combination of a vertically disposed frame having a laterally projected upper part, a pair of clamping members at the lower end of the frame for exerting pressure against the ends of the lower tier of brick, a pair of horizontally disposed long levers arranged crosswise of each other, means consisting of horizontal rock shafts having rigid arms thereon which are pivotally connected to the clamping members to provide a parallel 35 motion mechanism for each clamping member, whereby the power of said levers is applied to the clamps; and means for actuating said levers to effect the clamping.

5. A machine for handling bricks, comprising a vertical frame, a laterally extending arm on the upper end thereof, a single pair of laterally extending clamps at the base of the frame, rock shafts having arms movably connected to the clamps to provide a parallel motion mechanism for each clamp, 50 levers secured to the rock shafts, lifting bars pivoted to said levers, and means for raising the lifting bars when the lifting power is applied to lift the machine.

6. A machine for handling bricks, comprising a vertical frame, a laterally extending arm on the upper end thereof, supporting means carried by the outer end of said arm, a pair of laterally extending clamps carried by the lower end of the frame and 60 gripping the bricks, rock-shafts having rigid arms pivotally connected to said clamps to provide a parallel motion mechanism for each clamp for actuating the latter, and lifting bars pivotally connected to said levers 65 and jointly raised by the supporting means at the upper end of the frame.

7. A brick handling machine, comprising a main frame, an arm at the top thereof, supporting means carried by said arm, a 70 pair of clamps at the lower end of the frame, means for actuating the clamps consisting essentially of shafts each having a pair of arms pivotally connected to the clamps to provide a parallel motion mechanism for each clamp, levers arranged crosswise of each other and secured to the shafts, and connections between said levers and the arm at the top of the frame.

In testimony whereof I affix my signature 80 in presence of two witnesses.
